A technical drawing of a cylindrical component. A vertical tube is positioned in the center. The top of the tube is marked with a circle containing the letter 'B'. The bottom of the tube is marked with a circle containing the number '4'. Along the left side of the tube, there are two horizontal lines with the number '1' written above them. Along the right side of the tube, there are two horizontal lines with the number '10' written above them. At the very bottom of the tube, there is a small circle containing the number '5'. The base of the cylinder is shown with a hatched pattern.

John Unger,

Victor J. Evans

Attorney

UNITED STATES PATENT OFFICE.

JOHN UNGER, OF LOUISVILLE, COLORADO.

WHIFFLETREE ATTACHMENT.

No. 899,923.

Specification of Letters Patent.

Patented Sept. 29, 1908.

Application filed March 26, 1907, Serial No. 364,690. Renewed February 28, 1908. Serial No. 418,290.

To all whom it may concern:

Be it known that I, JOHN UNGER, a citizen of the United States, residing at Louisville, in the county of Boulder and State of Colorado, have invented new and useful Improvements in Whiffletree Attachments, of which the following is a specification.

This invention relates to hooks or attachments for whiffletrees for the purpose of retaining the tugs or traces in position thereon with no danger of displacement by the jolting or vibratory movement of the whiffletree when in use; and it has for its object to provide a spring actuated whiffletree hook 10 of simple and improved construction which may be readily applied in position for operation, which shall be safe and effective in operation, and which may be manufactured at a minimum expense.

20 With these and other ends in view which will readily appear as the nature of the invention is better understood, the same consists in the improved construction and novel arrangement and assemblage of parts which 25 will be hereinafter fully described and particularly pointed out in the claims.

In the accompanying drawings has been illustrated a simple and preferred form of the invention; it being, however, understood 30 that no limitation is necessarily made to the precise structural details therein exhibited, but that changes, alterations and modifications within the scope of the invention may be resorted to when desired.

35 In the drawing, Figure 1 is a top plan view showing the end of a whiffletree having the improved attachment applied thereto in position for operation. Fig. 2 is a rear elevation of the same. Fig. 3 is a rear elevation showing the whiffletree hook raised. Fig. 4 is a sectional view taken on the plane indicated by the line 4—4 in Fig. 3. Fig. 5 is a detail view of the whiffletree hook. Fig. 6 is a detail view of the bearing plate.

45 Corresponding parts in the several figures are denoted by like characters of reference.

The improved whiffletree attachment comprises a hook A and a bearing plate B.

50 The hook A is preferably formed, by bending, of stout spring wire, a piece of which a suitable length is bent or doubled upon itself to form the side members 1—1 that constitute the shank of the hook; the terminal portion of the wire being subsequently bent 55 to form the hook member 2, the free end 3 of which projects through or beyond the plane

of the extended shank formed by the side members 1—1. The terminal ends of the side members 1—1 are bent laterally in opposite directions to form arms 4—4 and the 60 extremities of said arms are bent upward or outward in the direction of the terminal hook 2 to form shoulders or offsets 8—8.

The bearing plate B consists of a piece of spring steel or other metal having longitudinal parallel incisions 6—6 whereby spring tongues 7—7 are formed at the edges of said plate, said spring tongues being bent or corrugated near their free extremities to form recesses or pockets 5 in the undersides thereof. In the end of the plate B, intermediate the incisions 6, there is formed a notch 9, and the tongues or strips of metal between said notch and the incisions 6 are bent back upon themselves to form eyes 10 wherein the arms 75 4 of the hook member A are pivotally mounted; the terminal shoulders or offsets 5 of said arms being extended beneath the spring tongues 7 and accommodated in the pockets or recesses 5 in the undersides of the latter. 80

The improved attachment may be applied to a whiffletree C of ordinary construction, being secured in place by suitable fastening members as shown at 11, in such a position that the free end 3 of the hook member will 85 extend through the aperture 12 near the end of the whiffletree.

The operation and advantages of this invention will be readily understood from the foregoing description taken in connection 90 with the drawings hereto annexed. When the device is in position for use, as indicated in Figs. 1 and 2 of the drawings, the hook member will serve to retain in position upon the whiffletree the cock eye of the tug or 95 trace, accidental displacement of the hook being prevented by the spring tongues 7 that engage the terminal shoulders or offsets 8 of the pivotal arms 4; the hook member may be readily raised to disengage the free end 3 100 from the eye 12 for the purpose of adjusting or removing the trace, but when released it will spring back, under the tension of the springs 7 to the normal or locked position indicated in Figs. 1 and 2. If desired, the 105 hook member A may, however, be raised to the position indicated in Fig. 3, when the shoulders or offsets 5 are on the dead center, or past said position in the direction of the arrow, when it will be retained in non-engaging 110 position as regards the eye 12 by the action of the spring tongues 7.

This improved device, as will be seen, is extremely simple in construction and operation, and it may be manufactured at a very trifling expense.

5 Having thus fully described the invention, what I claim as new is:—

- 10 1. A whiffletree attachment comprising a hook member and a bearing plate, said hook member having a doubled portion constituting a hook and a shank and laterally extended arms formed with terminal shoulders or offsets, and said bearing plate being provided with longitudinal incisions, an intermediate notch, bent portions forming spring 15 tongues at the edges of said plate and intermediate eyes wherein the arms of the hook member are pivoted.

2. An article of the class described comprising a bearing plate having spaced eyes and resilient tongues adjacent to said eyes and provided with recesses or pockets in their undersides, in combination with a hook member having a shank composed of side members formed with laterally extending arms pivotally engaging the eyes of the bearing plate and having terminal shoulders or offsets engaging the pockets or recesses in the undersides of the resilient tongues. 25

In testimony whereof, I affix my signature in presence of two witnesses.

JOHN UNGER.
